(57) **CLAIM**

I claim the ornamental design for a pet waste pickup device, as shown and described herein.

DESCRIPTION

FIG. 1. Is a perspective view of my pet waste pickup device; FIG. 2 is a right side elevational view thereof; the left side elevational view being identical thereto;

FIG. 3. Is a front view thereof;

FIG. 4. Is a rear view thereof;

FIG. 5. Is a top view thereof; and,

FIG. 6. Is a bottom view thereof.

The broken line portions of the disclosure are for illustrative purposes only and form no part of the claimed design.
